United States Patent Office.

GEORGE H. SMITH, OF GALESBURG, ILLINOIS.

Letters Patent No. 97,819, dated December 14, 1869.

IMPROVEMENT IN SMOKE-CONSUMING FIRE-BOXES.

The Schedule referred to in these Letters Patent and making part of the same.

To all whom it may concern:

Be it known that I, GEORGE H. SMITH, of Galesburg, in the county of Knox, and State of Illinois, have invented a new and improved Smoke-Consuming Fire-Box; and I do hereby declare that the following is a full, clear, and exact description thereof, which will enable those skilled in the art to make and use the same, reference being had to the accompanying drawings, forming part of this specification.

This invention relates to a new and improved method of building fire-boxes and furnaces, whereby the smoke and gaseous products of combustion which pass upward from the fuel and from the fire-box are returned thereto, and subjected to a high temperature and consumed.

The invention consists in the formation of a fire-brick fire-box, covered with a cap or dome of metal or other suitable material; and in a flue or pipe, made of fire-brick or fire-clay, or other suitable material, arranged within the fire-box, through which the smoke and gaseous products of combustion are made to pass, as hereinafter is more fully described; and in a provision for the admission of oxygen from outside of the furnace to mingle with said products of combustion in their passage from the fire-box, and assist their consumption.

Figure 1 is a vertical section of the furnace or fire-box, through the line *z z* of fig. 2.

Figure 2 is a vertical section through the line *y y* of fig. 1.

Similar letters of reference indicate corresponding parts.

A is the fire-box.

C represents the grate-bars.

D is the dome or combustion-chamber above the fire-box proper. This dome may be made of metal or fire-brick, or other good heat-resisting material.

The fire-box is made of fire-brick, or lined with that or other incombustible material.

E is a pipe, placed horizontally in the fire-box, made of fire-brick or other incombustible material, extending across the fire-box into the space between it and the outer casing of the furnace.

It is perforated at intervals with small openings *a a*, through which a small portion of the flame from the fire-box may jet into the interior of the pipe.

F is a flue, extending from near the crown of the dome *D* to the perpendicular flue *G*, which, descend-

ing between the outside of the fire-chamber and the exterior casing of the furnace, has free communication at its bottom with one end of the pipe *E*.

The other end of the pipe *E* opens into a similar flue, *H*, rising up on the opposite side of the fire-chamber and leading to the stack.

b is a small pipe, extending from outside of the outer casing of the furnace to the inside of the descending-flue *G*, into which it opens at or near the open end of the pipe *E*, and may be provided at its outer end with a stop-cock, if deemed expedient. The smoke and gaseous products of combustion rise into the dome as the fuel is consumed, and pass from the dome through the pipe *F* into the vertical pipe *G*, from whence they escape into the fire-pipe *E*. This pipe, from its position immediately over the fire, is heated to a high degree at all times when the fire is burning, so that the smoke and gases which enter it are subjected to a very high temperature, and are consumed, or are so nearly consumed that the quantity escaping through the pipe *H* to the chimney is too small to be objectionable under any circumstances.

The pipe *b* admits a small portion of air from the outside of the furnace to the interior of the pipe *E*, the oxygen of which, mingling with the inflammable contents thereof, and augmented in its power by the jets of flame through the openings *a a*, greatly assist and expedite the operation, and insures the combustion of matter in the flue before it reaches the stack.

I is the door, for the introduction of the fuel;

J represents the ash-pit; and

K the ash-pit door.

The whole furnace may be surrounded by a wall and arch of brick-work or masonry, as represented in the drawing.

I claim as new, and desire to secure by Letters Patent—

1. The pipe *E* or its equivalent, with or without perforations *a a*, and the pipe *b*, in combination with the fire-chamber of a furnace, substantially in the manner and for the purpose set forth.

2. The pipe *E*, perforated as shown, or its equivalent, and the pipe *b*, in combination with the flues *F G H* of a furnace, and arranged substantially as specified.

GEORGE H. SMITH.
